UNITED STATES PATENT OFFICE

WILLIAM J. SCHMIDT, OF CHICAGO, ILLINOIS

TABLE

Application filed March 8, 1930. Serial No. 434,420.

This invention relates to furniture, bric-a-brac and decorative objects, to methods and means for fabricating the same, and more especially to the elemental peculiarities characterizing a certain species of structural design adapted for embodiment in many variant forms of furniture and decorative goods.

The main objects of the invention are to provide a simple, improved and more decorative method of constructing or fabricating various objects of utility, especially household furniture; to provide such a method comprising mainly the repetitious elaboration of a simple or elementary structural design; and by such a method to produce a variety of useful and decorative articles, such as tables, picture frames and numerous kindred devices, all characterized substantially by a dominant elemental joint design.

20 An illustrative embodiment of this invention is shown by the accompanying drawing, in which:—

Figure 1 is a side view of a square table, the top boards being indicated by dotted lines.

Fig. 2 is a view of the table of Fig. 1 as viewed from either the right or the left.

Fig. 3 is a perspective view of a characteristic elemental six-bar mortised joint design unit.

Fig. 4 is a perspective view of the mortised side of an illustrative elemental bar trebly mortised for selective use in variant structural designs.

35 Fig. 5 is a fragmentary plan showing the corner at the right of Fig. 1 and at the left of Fig. 2.

Fig. 6 is a side view of an elemental joint with two of the resilient bars sprung apart at one end to admit the complementary bar member.

Referring to the drawing, the table 1 comprises a rectangular frame 2, four corner legs 3 and a flat board top 4. Said frame comprises on each side a pair of similar spaced parallel bars 5. On two opposite sides A these bars lie side by side, as shown in Fig. 2, and on alternate sides B they lie one over the other, as shown in Fig. 1.

Each of said legs 3 comprises a pair of similar upright spaced parallel bars 6.

Said frame bars 5 and leg bars 6 are all similarly mortised on their inner faces, as at 7, where they cross and, as at 8, are mutually united in substantially rigid frame joint arrangement, such as illustrated by Figs. 6 and 3.

In order to readily accommodate decorative embellishment, and to facilitate variations in specific design, the several bars 5 and 6 also have additional mortises similar to those indicated at 7. For convenience in manufacture and fabrication and for the sake of standardization and economy, the several bars are all cut from common bar stock 9 preformed in any desired commercial or storage lengths and having a uniform continuous series of appropriately spaced mortises 7.

For the sake of neatness and economy, the material between mortises is preferably cut out as at 10, leaving inclined inactive shoulders 11 and 12. The mortise shoulders 13 are preferably upright and parallel.

As a net result the bars are all flattish as a whole, with the mortises on one side, and responsive to appropriate bending of the bar between shoulders to more or less open and occlude the mortise openings, as will be understood.

The bars, or at least part of them, are positively somewhat flexible and resilient, so as to permit such assembly as illustrated by the joint unit 14 of Figs. 6 and 3. Properly selected wood, as for instance, cedar or pine, is well adapted for the purpose, and for most light work is preferred.

Referring further to the drawing, the table 1 may be provided with any sort of a top desired, as indicated by dotted lines at 4. Furthermore, for artistic effect or other purposes, additional or supplementary frame and leg members 22 and 23 may be added substantially similar to members 2 and 3 respectively, as shown, in which event horizontal foot members 25 may well be provided, to harmonize with the corresponding overlying corner parts of frame 2.

The most convenient method for assembling a joint unit 14, such as shown in Fig. 3

and such as appears throughout the fabricated objects referred to, is to first arrange five of the members in due joint relation and then deftly snap the sixth member wedgingly into place, as indicated in Fig. 6. Incidentally, the wood is somewhat resiliently compressible, and this further facilitates assemblage. This joint forming process is repeated throughout the structure and in some devices may be extended indefinitely, as will be apparent.

Although preferred details for the process and product of this invention are herein set forth, it is to be understood that some of the details recited may be modified or omitted without departing from the spirit of the invention as defined by the following claim.

I claim:

A table or the like having a rectangular frame and a plurality of legs and comprising on each side a pair of similar frame bars disposed horizontally and at each corner a pair of upright leg bars, each pair of leg bars and the adjacent portions of the side bars being similarly mortised with spaced shoulders and being mutually interlocked.

Signed at Chicago this 15th day of January, 1930.

WILLIAM J. SCHMIDT.
